UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

LOCK.

SPECIFICATION forming part of Letters Patent No. 378,268, dated February 21, 1888.

Application filed November 12, 1887. Serial No. 255,012. (No model.)

To all whom it may concern:

Be it known that I, WARREN H. TAYLOR, of Stamford, in the county of Fairfield and State of Connecticut, have invented a certain 5 new and useful Improvement in Locks, of which the following is a specification, reference being had to the accompanying drawings.

My invention relates particularly to that class of locks in which the tumblers are contained in a separate escutcheon or tumbler-case—such, for instance, as the well-known Yale locks; and it has for its object the prevention of the removal of this escutcheon or tumbler-case, except by one who is in possession of the key for unlocking the lock, and who, therefore, may be presumed to have the right to remove the escutcheon.

The usual method of fastening an escutcheon in place is by means of a set-screw passing 20 through the face of the lock and engaging with a groove or other depression in the periphery of the escutcheon, so that when the set-screw is turned out the escutcheon can be removed. There are also other methods of 25 fastening in the escutcheon; but heretofore locks have been so constructed that when the door was open and the face-plate accessible any person with a screw-driver or the point 30 of a knife could release the set-screw or other stop, so that the escutcheon could be unscrewed or otherwise removed. If such person desired to effect an entrance to the room or house, he could release the set-screw or other stop sufficiently, so that while the turning 35 of the key to throw the bolt would not turn the escutcheon the escutcheon could be turned by the application of slight force. Then, after the owner had left the door locked, as he supposed, the evil-disposed person could 40 return and unscrew the escutcheon, or otherwise remove it, and have access to the interior of the lock, so that he could unlock it. My invention removes this source of weakness and provides a fastening for the escutcheon 45 in the interior of the lock, which can only be released by means of the proper key acting through the escutcheon itself. It is evident

that if any one has the proper key to the lock he can gain access to the room, and so will have no object, except a proper one, in removing the escutcheon. 50

My invention consists in the special means of fastening an escutcheon within the interior of a lock, as hereinafter specified, and succinctly summed up in my appended claim. 55

In the accompanying drawings, Figure 1 is a view of a lock containing my improvement, one plate of the lock being removed; and Fig. 2 is a view of one side of an escutcheon detached. 60

Referring to the letters upon the drawings, A indicates a lock-case, B a lock-bolt, and C a screw-threaded escutcheon set into the case in the usual way. D indicates a set-screw, and E a forked slide adapted to enter the 65 grooves in two opposite escutcheons and hold them in place.

The devices thus far described are all old.

Coming to what is new, I provide a tail-piece, F, upon the key-plug X, which projects 70 below the periphery of the escutcheon when the plug is in the proper position for removing the key, as shown in Fig. 1. This tail-piece or projection in that position bears upon or engages with the lock-case, so that the 75 escutcheon cannot be unscrewed or removed; but when the key is inserted and the plug turned part of a revolution the tail-piece will assume the position shown in dotted lines, when the escutcheon can be unscrewed 80 and removed after removing the ordinary set-screw escutcheon-fastening, E. (Shown in Fig. 1.)

This invention is adapted to be used with different varieties of locks having escutcheons 85 or tumbler-cases of similar nature.

In the drawings are shown several ordinary parts of a lock which I do not describe, because they form no part of this invention.

I have taken out a United States Patent, 90 No. 373,253, in which I show several varieties of devices of this general nature for securing escutcheons in place, and in which I have made a broad claim, and I therefore do not

claim in the present case more than the peculiar device herein described, which is not specifically claimed in said patent.

I claim—

5 The combination, with an escutcheon and key-hub, of a tail-piece or projection from the hub adapted to bear against the lock-case and prevent the unscrewing or removal of the

escutcheon, except by use of the key, substantially as set forth.

In testimony whereof I have hereunto subscribed my name.

WARREN H. TAYLOR.
